UNITED STATES PATENT OFFICE.

PORTER S. MORGAN, OF NEW YORK, N. Y.

POWER-OPERATED BRAKE.

Application filed December 26, 1919, Serial No. 347,590. Renewed February 3, 1925.

To all whom it may concern:

Be it known that I, PORTER S. MORGAN, a citizen of the United States, and a resident of New York, in the county and State of New York, have invented certain new and useful Power-Operated Brakes, of which the following is a specification.

My invention relates to brakes, in which a primary and secondary band are used; 10 the primary band being initially set and by its angular rotation with the drum sets the secondary brake band through means connected therewith.

The objects of my invention are; first, 15 to provide a brake that is set by power for either direction of rotation of the brake drum; second, to provide a power brake in which the operating force is proportional to the speed of the moving drum or vehicle, 20 and third, to provide a brake in which the secondary brake band may be set independently or co-operatively with the primary band.

The above enumerated objects and others 25 that will later on appear are now to be described and are illustrated in the accompanying drawing forming a part of this specification.

Similar characters of reference denote 30 like or corresponding parts throughout the several views, of which Fig. 1 is a side elevation of my brake as applied to one wheel of a motor vehicle and Fig. 2 is a section on the line A—A of Fig. 1.

Referring particularly to Fig. 1, the 35 numeral 3 represents the axle, 4 the axle casing, 5 a stationary spider secured to this casing, 6 the brake drum, 7 an internal expanding brake band having spaced apart 40 ends 8 and 9 with flat parallel faces, and 10 an external contracting brake band, both 45 brake bands being held normally out of contact with the brake drum. Between the 50 ends 8 and 9 are placed two cams, one 45 of which 12 is secured to a tube 13 journaled in the spider 5, and the other 11, secured to a shaft 14 journaled in the tube 13. Secured to the shaft 14 is a lever 15 connected, by the link 16 to the hand 55 lever 17. This hand lever is adapted to move the link 16 in the direction of the arrow 19 for rotating the cam and spreading apart the ends 8 and 9 for setting the 60 secondary brake. The notched quadrant 18 56 is for holding the hand lever in any position of brake setting desired. A stud 20

is secured in the spider 5 and engages the slot 21 in the center of the band 7 to hold this band in a central position when clear of the drum 6. The spring 22 is for holding the ends 8 and 9 tightly against the cam 12 and for returning this cam to its normal position (as shown), when released.

Secured to the tube 13 is a gear quadrant 60 23 meshing, with a circular rack sector 24 attached to the primary brake band 10 so that an angular rotation of the last-mentioned band in either direction will rotate the cam 12 and cause the secondary brake band 7 to frictionally engage the drum 6.

The band 10 has spaced apart ends 25 and 26, connected by a bell-crank lever 27 and adjustable eye rod 28, for drawing together the ends of the band and setting the 70 brake through the link 29 and the foot pedal 30.

The operation of my brake is as follows; 75 assume the drum to be rotating in the direction of the arrow 32, by pressing the foot pedal the link 29 will be moved in the direction of the arrow 34 and the primary brake band 10 brought into contact with the rotating drum. As this band is free to rotate, it turns with the drum and, through the intermediary of the rack 24 and quadrant 80 23 rotates, the cam 12 and sets the secondary brake. When the foot is removed from the pedal the band, being free to rotate, is turned back to its normal position by the spring 22, forcing the cam and with 85 it the quadrant 23 back to the central position. If the drum is rotating in the direction of the arrow 33, the primary band 10, after being applied, will rotate in this same direction and will turn the cam 12 in a 90 direction opposite to that first described, and will still spread the inner brake band 95 and apply the brake.

The hand lever 17 may be operated to 100 set the inner brake band either simultaneously or independently of the power brake setting.

Having thus fully described and illustrated my invention so that anyone skilled in the art may make and construct the same, I 105 claim:

1. In a power operated brake, in combination, a brake drum; a primary brake band; a secondary brake band, each of said 110 brake bands having spaced ends; means for drawing together the spaced ends of said primary band to thus effect engagement

- with said drum; an operating lever therefor connected directly with said means; means whereby rotary motion of said primary band imparted by said engagement may effect an engaging motion of said secondary band with respect to the drum, comprising a rack secured to said primary brake band, a rack sector engaging therewith, and a cam operatively connected with said rack 10 sector and interposed between the spaced ends of the secondary brake band, said sector being the only actuating means for said cam.
2. In a brake, in combination, a brake drum; primary and secondary brake bands engaging said drum; means connected with the primary brake band only to cause it to engage the drum; and means for actuating the secondary brake band to cause it to engage the drum, said latter means comprising a rack secured to the primary brake band, a rack sector engaging therewith and a cam operatively connected to said sector and cooperating with the secondary brake band to 25 actuate it.
3. In a brake, in combination, a brake drum; primary and secondary brake bands engaging said drum, means connected with the primary brake band only to cause it to engage the drum; and means for actuating the secondary brake band to cause it to engage the drum, said latter means comprising a rack secured to the primary brake band, a rack sector engaging therewith and a cam 30 operatively connected to said sector and cooperating with the secondary brake band to actuate it; together with means for actuating the secondary brake band independently of the primary brake band.
4. In a brake, in combination, a brake drum; primary and secondary brake bands engaging said drum; means connected with the primary brake band only to cause it to engage the drum; and means for actuating the secondary brake band to cause it to engage the drum, said latter means comprising a rack secured to the primary brake band, a rack sector engaging therewith and a cam 40 operatively connected to said sector and cooperating with the secondary brake band to actuate it; together with independent means for actuating the secondary brake band comprising a cam coaxial with the first mentioned cam.
5. A brake of the character described comprising a brake drum; a primary brake band and a secondary brake band engaging said brake drum; means to operate the primary brake band only to cause it to engage the 50 brake drum with a part wrap and a part unwrap action; independent means controlled by the primary brake band for actuating the secondary brake band with a part wrap and part unwrap action, said latter means comprising a cam; together with independent 55 means for actuating the secondary brake band comprising a cam coaxial with the first mentioned cam.
6. The combination with a brake drum, of an outer primary brake band and an inner 70 secondary brake band carried adjacent said drum, said secondary brake band having spaced apart ends, means connected to the ends of said primary brake band to effect its engagement with said drum, and means independent of the first mentioned means operatively connecting said brake bands and comprising a cam interposed between the ends of said secondary brake band, a rack sector secured to said primary brake band 75 and a gear segment attached to said cam and meshing with said rack sector, whereby an angular rotation of said primary brake band actuates said cam to set said secondary brake band.
7. In a power operated brake, in combination, a brake drum; a primary brake band; a secondary brake band having spaced ends; means to effect the engagement of said primary brake band with the brake drum where- 80 by rotary motion of the drum will be imparted to said primary brake band; and means whereby said rotary motion may effect an initial engaging motion of said secondary band with respect to the drum, comprising a rack secured to said primary brake band, a rack sector engaging therewith and a cam 85 operatively connected to said rack sector and interposed between the spaced ends of the secondary brake band.
8. In a power operated brake, in combination, a brake drum; a primary brake band; a secondary brake band having spaced ends; means to effect the engagement of said primary brake band with the brake drum where- 90 by rotary motion of the drum will be imparted to said primary brake band; and means whereby said rotary motion may effect an initial engaging motion of said secondary band with respect to the drum comprising a 95 rack secured to said primary brake band, a rack sector engaging therewith, and a cam operatively connected to said rack sector and interposed between the spaced ends of the secondary brake band.
9. In a power operated brake, in combination, a brake drum; a primary brake band; a secondary brake band having spaced ends; means to effect the engagement of said primary brake band with the brake drum where- 100 by rotary motion of the drum will be imparted to said primary brake band; and means whereby said rotary motion may effect an initial engaging motion of said secondary band with respect to the drum comprising a 105 rack secured to said primary brake band, a rack sector engaging therewith, and a cam operatively connected to said rack sector and interposed between the spaced ends of the secondary brake band; and separate means 110 for actuating said secondary band for engagement with said drum.
10. In a power operated brake, in combination, a brake drum; a primary brake band; a secondary brake band having spaced ends; means to effect the engagement of said primary brake band with the brake drum where- 115 by rotary motion of the drum will be imparted to said primary brake band; and means whereby said rotary motion may effect an initial engaging motion of said secondary band with respect to the drum, comprising a 120 rack secured to said primary brake band, a rack sector engaging therewith, and a pair of cams interposed between the spaced ends of 125

the secondary brake band, connections between one of the said cams and said rack sector whereby motion of the primary brake band will be transmitted to the secondary brake band; and means for moving said second cam independently of the first to actuate said secondary band.

10. A brake of the character described comprising a brake drum; a primary brake band and a secondary brake band engaging said brake drum; means to operate the pri-

mary brake band only to cause it to engage the brake drum with a part wrap and a part unwrap action; and means controlled entirely by the primary brake band for actuating the secondary brake band with a part wrap and a part unwrap action. 15

Signed at New York in the county of New York and State of New York this 16th day of Dec. A. D. 1919.

PORTER S. MORGAN.
